UNITED STATES PATENT OFFICE.

CHARLES T. WITTSTEIN, OF NEWARK, NEW JERSEY.

DESIGN FOR A GEM-SETTING.

46,521.

Specification for Design.

Patented Oct. 6, 1914.

Application filed June 25, 1914. Serial No. 847,320. Term of patent 14 years.

To all whom it may concern:

Be it known that I, CHARLES T. WITTSTEIN, a citizen of the United States, residing at Newark, in the county of Essex and State of New Jersey, have invented a new, original, and ornamental Design for a Gem-Setting, of which the following is a specification, reference being had to the accompanying drawing, forming part thereof.

Figure 1 is a plan of a gem setting em-

bodying my invention, and Fig. 2 is a side view thereof.

I claim:

The ornamental design for a gem setting as shown.

CHARLES T. WITTSTEIN.

Witnesses:

HOWARD P. KING,
JANET A. AYERS.
